APPARATUS FOR APPLYING MATERIAL TO PARTS

Albert Jones, Jersey City, N. J., assignor to Western Electric Company, Incorporated, New York, N. Y., a corporation of New York

Application February 8, 1939, Serial No. 255,260

1 Claim. (Cl. 144—280)

This invention relates to an apparatus for applying material to parts, and more particularly to an apparatus for uniformly gluing parts together.

The strength of the joint of two wood parts joined by gluing depends upon the uniformity of application of the glue between the parts. In applying glue to parts by one of the well known methods, that is, by brushing, it is difficult, if not impossible, to apply the glue uniformly throughout the surfaces to be glued and with suitable thinness to form a joint of greatest strength and avoid an overflow of glue from between the parts.

An object of the invention is to provide a simple, efficient and practical apparatus for applying material to parts.

With this and other objects in view, the invention comprises an apparatus for holding one part while predetermined quantities of glue are definitely disposed upon another part at spaced positions so that the placing of the second or glue applied part to the held part, causing a definite relative movement of the parts to cause the glue to be distributed between the surfaces of the parts to form a uniform joint of greatest strength.

Other objects and advantages will be apparent from the following detailed description when taken in conjunction with the accompanying drawings, wherein

Fig. 1 is a top plan view of the apparatus;

Fig. 2 is a side elevational view of the apparatus, portions thereof being broken away;

Fig. 3 is a perspective view of the glue applying element, and

Fig. 4 is a fragmentary perspective view illustrating two parts joined together.

Referring now to the drawings, it will be noted that the apparatus in general consists of a glue applying means indicated generally at 10 and a holding means indicated generally at 11, both of which are supported by a table 12 having supporting legs 13. The glue applying means 10 comprises a glue pot 15 of any suitable type, for example, the conventionally electrically heated type, mounted in an aperture in the table 12 so that the opening in the glue pot will be positioned but a slight distance above the upper surface of the table. An element 16 is constructed to remove from the glue pot definite quantities of glue 17, which quantities of glue may be transferred to end parts 18, which are to be joined to a central part 19. The specific contour of the parts 18 and 19 is immaterial, but to illustrate

the invention the central part 19 has reduced ends 20 equal in contour to the surfaces of the end parts 18 to be positioned in engagement therewith and joined thereto. These reduced ends 20 form vertical walls 21 conditioned to lie flush with portions of the inner walls of the parts 18. Therefore, in order to form the most efficient glued joint between the parts 18 and the part 19, the element 16 is constructed so as to apply predetermined quantities at spaced positions along the lower surfaces of the parts 18 and along the inner walls thereof distances equal to the depth of the wall 21 of the part 19. The element, therefore, is constructed of a plurality of glue applying segments or members 24 provided with aligned apertures for receiving retaining members such as bolts 25 and spaced from each other predetermined distances determined by the width of washers 26 mounted upon the bolts 25 between the members. Each member 24 has a raised portion 28 adjacent the center of its upper surface, these portions being of any desired width depending upon the width of the inner surfaces of the parts 18 to be glued. The ends of these portions 28 are in alignment, as illustrated in Fig. 3.

Means is provided for moving the element 16 into and out of the glue pot 15, this means comprising an arm 30 having its lower end resting upon certain of the members 24, as illustrated in Fig. 2, where it is secured in place by suitable means, such as machine screws 31, extending through a plate 32, positioned beneath the element 16, extending between certain of the members 24 and having their threaded ends embedded in the lower end of the arm. The upper end of the arm 30 is connected to one end of a lever 33 by suitable means, such as a bolt 34, capable of securing the arm to the lever in any desired angular position so as to determine the position of the element 16 relative to the table 12 when raised out of the glue pot. The lever 33 is pivotally supported, at 36, by a bracket 37 mounted upon the table 12, and has its other end operatively connected to a foot treadle 40 by a link 41. The foot treadle is pivotally supported at 42 by a suitable bracket connected to a cross-bar between the legs 13 and is normally urged into upper position to normally position the element 16 in the glue pot by means of a tension spring 43, the latter having one end fixed to the table while the other end is connected to the link 41.

The holding means 11 is composed mainly of an adjustable stationary element 46, a movable

element 47, and means to cause movement of the latter. The stationary element 46 has elongate apertures 48 therein for receiving securing members such as carriage bolts extending through the apertures 48 and through apertures in the table 12, where their lower threaded ends are provided with wing nuts so that the element 46 may be adjusted relative to the movable element 47 depending upon the width of the parts being joined. The forward central portion of the element 46 has an arcuately cut away portion 50 so that the element may be moved beyond the forward edge of the table without interfering with the operator. The element 46 is also provided with arcuately cut away portions or recesses 51 positioned in general alignment with similar recesses 52 of the element 47, providing space upon each side of the part 19 for the operator to grip the part and readily remove it and insert a new part in place. By viewing Fig. 2, it will be observed that the element 46 is slightly thinner than the reduced ends of the part 19, while the element 47 is slightly thicker than the thickest portion of the part 19. The purpose of these dimensions will be hereinafter described.

The element 47 is slidably mounted upon the upper surface of the table 12 and has its ends positioned in guideways 55. The means for imparting movement to the element 47 consists of a foot treadle 56 pivotally supported, at 57, by a bracket carried by the crossbar between the legs 13. A link 60 connects the treadle 56 to an arm 61 which is fixed to a shaft 62. The shaft 62, as illustrated in Fig. 2, has its ends journaled in suitable bearings 63, 64 and 65 and supports spaced vertical arms 67 and 68 which have their lower ends fixed to the shaft. The upper ends of the arms 67 and 68 are pivotally connected to angular brackets 69, the latter being secured to the element 47 as illustrated in Fig. 1. Helical tension springs 70, having their inner ends fixed to the table 12 in elongate apertures provided for the movement of the arm 67 and their rearward ends connected to the arms 67, provide means to normally urge the element 47 toward the element 46 and to normally hold the treadle 56 in upward position. A stop 72 serves two purposes, one to limit the forward movement of the element 47 when there are no parts 19 disposed between the elements 46 and 47 and to serve as a locating means for the parts 19 when disposed in place between the elements.

Referring now to the operation of the apparatus, attention is first directed to the fact that both treadles are normally held in their upper positions by their respective springs, normally positioning the glue applying element 16 in the glue pot and normally urging the holding element 47 toward the element 46. The apparatus has been designed to hold two of the parts 19 at one time in order to increase production and decrease the effort of the operator in actuating the holding means. The first step in the operation is to open the holding means by pressing downwardly upon the treadle 56 to move the element 47 away from the element 46 against the tension of the springs 70. While the elements are in this position the operator may readily insert two parts 19, simultaneously if so desired, upon each side of the stop 72, the stop assisting the operator in locating the parts so that at all times they will be disposed in definite positions. The treadle 56 is then released, allowing the spring 70 to cause movement of the element 47 to form a gripping engagement of the parts 19.

between the elements 46 and 47. In the next step in the operation the operator having a part 18 in each hand, lowers the treadle 40 to the position shown in solid lines in Fig. 2, causing movement of the element 16 out of the glue pot, taking with it definite and predetermined quantities of glue which rest upon the upper surface of the element 16 and also upon the end surface of the projections 28, the excess quantities of glue passing between and upon the outside of the members 24 and dropping into the glue pot. The operator at this time places the parts 18 upon the element 16 in the positions shown in Fig. 3, their lower surfaces resting upon the upper edges of the members 24 and their inner surfaces engaging the end walls of the portions 28 to receive therefrom the quantities of glue. The width of the members 24 determines the quantity of glue disposed upon the surfaces of the parts 18 and the spaces between the members determine the number and spacing of these quantities. Furthermore, with this means definite quantities of glue are disposed at spaced positions throughout the surfaces to be glued, these quantities being equal to assure equal application of the glue throughout the surfaces. The positioning of the glue pot with its upper surface adjacent the top of the table 12 enables the operator to rest his arms and portions of his hands upon the table so as to easily and accurately position the parts upon the element 16. In this manner the parts 18 and the element 16, if so desired, may be moved toward the glue applying position at the same time.

After the glue has been applied to the parts 18 the treadle 40 is released, allowing the spring 43 to cause the element 16 to be returned to the glue pot. The parts 18 are then placed upon the reduced ends 20 of one of the parts 19 so that the inner surfaces of the parts 18 will engage their respective walls 21. At this time the parts 18 are moved longitudinally to spread portions of the spaced quantities of glue over the unglued portions, causing a uniform application of the glue between the surfaces being joined, and finally positioning the parts 18 in close engagement with the element 47, which serves to definitely and accurately locate the parts 18 on the parts 19. This completes the joining of one part 19 with two of the parts 18. The remaining part 19 held between the elements 46 and 47 may have parts 18 joined at the ends thereof by carrying out the same steps of the method previously described.

When the apparatus is in use, definite known quantities of glue are disposed upon definitely spaced portions of the surfaces of the parts to be joined to the part 19 and by placing the parts 18 upon the part 19 the first portions of the surfaces of the part 19 coming in contact with the spaced deposits of glue receive portions of these deposits and by relative movement of the parts 18 and the part 19 other portions of these deposits are spread upon the unglued surfaces and, due to the fact that equal quantities of glue are disposed equal distances apart on the surfaces, equal portions of these quantities may be spread upon the unglued surfaces, equalizing the application of the glue throughout the surface areas being joined, thus forming the strongest joint possible by gluing, eliminating waste of glue, providing a neat joint, and eliminating the necessity of the removal of excess glue. The thickness of the element 46 permits movement of the parts 18 without the possibility of causing

the deposit of glue upon the element, while the element 47 is of sufficient thickness to hold the part 19 in place and serve as a stop for the parts 18 to be accurately brought into position with the part 19.

The embodiment of the invention herein disclosed is illustrative only and may be widely modified and departed from in many ways without departing from the spirit and scope of the invention as pointed out in and limited only by the appended claim.

What is claimed is:

In an apparatus for use in applying material to parts, a container of material, a material applying means having a plurality of like rigid

members formed with sets of lateral upper material applying surfaces and rigid projections interposed singly between the surfaces of each set, said projections having rigid material applying end surfaces lying in a pair of spaced planes transversely to a plane of the lateral surfaces and extending above the lateral surfaces, and means to cause movement of the material applying means from the container to cause the said surfaces to remove quantities of material therefrom and deposit the quantities of material at definite spaced positions on adjacent lateral and angular surfaces of a plurality of parts.

ALBERT JONES.
